Chas. Wilcox Attn:

UNITED STATES PATENT OFFICE.

HARRY J. LYONS, OF GENEVA, ILLINOIS, ASSIGNOR TO GENEVA HEATER COMPANY, OF GENEVA, ILLINOIS, A CORPORATION OF ILLINOIS.

AUTOMATIC WATER HEATER.

Application filed July 28, 1924. Serial No. 728,529.

The invention hereinafter described pertains to water heaters and has reference more particularly to that type known as automatic heaters.

In water heaters of the above mentioned type, a serious disadvantage has been found. The thermostat is located in the discharge pipe from the heating coils. When the water passing through the thermostat reaches

10 a predetermined temperature, the thermostat operates the gas supply valve or means controlling the gas supply valve to reduce the flow of gas to the heater or to shut off the gas entirely. If the faucet remains open

15 while the gas valve is closed or nearly closed, the water flowing through the coils will not be heated until the cold water issuing from the coils actuates the thermostat to turn on the gas again. The result is that a quantity

20 of cold water is delivered from the faucet.

It is, therefore, the primary object of my invention to eliminate the effects of this lag in heating by so arranging the thermostat and heating coils that water drawn from the 25 hot water faucets will be at a substantially uniform temperature at all times, and, regardless of whether or not the burners are automatically shut off by the thermostat during the period of use of the water heater.

30 Further objects will become apparent from the description and claims and from the drawing in which the figure is an elevation of one form of my invention, parts being broken away to show the interior construction of a heater to which it is applied.

The heater comprises an outer shell 2 supported upon a base 4 which is in turn supported upon suitable legs or standards 6 and at the top has the usual flue 8 and cap 10 arranged to form together with the base and shell, an inclosing housing for the heater elements. Water is admitted to the circulating system through a cold water inlet 12 in connection with which the thermostatically

40 regulated by-pass valve 13 is arranged. A pipe 14 passes downwardly therefrom and back of the water valve 16 to the manifold indicated at 18 connecting the lower or primary heating coils 20 in parallel. At the

45 top of this primary group of coils 20, a second manifold 22 receives the water discharged therefrom and directs it through a downwardly extending pipe 24 into the base of a thermostat pipe 26 connected at its upper end through a pipe 28 and a second dis-

tributing manifold, generally indicated at 30, to the top or secondary group of heating coils 32 which may be connected at their lower ends through a manifold 34 to the hot water outlet 36. At the base of the thermostat and at substantially the lowest portion of the heater circulation system I provide a petcock or other valve 38 for drainage purposes.

The fuel burners comprise the usual elements 40 positioned axially of and concentrically within the primary group of water circulating coils 20 and may be connected through a water by-pass gas control valve 42, such as that shown in the patent to Ahlberg, No. 667,356 of February 5, 1901, or that shown in Toombs, No. 1,398,755 of November 29, 1921, which is in turn supplied with fuel from any supply source. The usual pilot light or lights 41 (one shown) may be supplied to ignite the fuel emanating from the burners 40 as will be understood. The water and gas valves will not be further described since their operation is fully described in the patent to which I have referred above.

The thermostat 26 may be constructed and arranged to control the by-pass valve adjacent the cold water inlet through the medium of lever 44, plunger 46 and adjusting screw 48.

When a heater unequipped with my invention operates, it sometimes happens that the water temperature becomes high enough to cause the thermostat to operate to completely close the fuel supply valve so that the water passes through the heating coils without being heated. Since the burner is closed off, the cold slug of water passes through the system and out of the hot water outlet, greatly to the consternation of the user. With my invention it will be clearly seen that this objection is obviated, for should the thermostat operate to shut off the gas during a period at which the hot water faucet is open, the unheated water will pass through the lower or primary group of coils only and thence into the thermostat pipe, causing the thermostat to contract and reopen the fuel valve to the burners, by operation of the by-pass valve, before the cold water following has passed through the upper or secondary group of coils into the hot water outlet. In other words, the cold slug of water which has passed through the

primary coils will be subjected to heat rising from the burners 40 while it is passing through the secondary coils and before it has had time to pass from the hot water outlet to the faucet.

Various modifications of the invention will be obvious for it will be appreciated that the upper and lower groups of coils need not be arranged one above the other, 10 provided they are placed in a heating zone and the thermostat or other control means be placed intermediate the ends of the heater circulating system. It will also be obvious that my invention may be readily applied 15 to other water heaters and fluid apparatus regulated thermostatically or by similar mechanism, whether a by-pass or other control be used or not, and for that reason I desire to be limited only by the spirit of 20 my invention and the scope of the appended claims.

I claim:

1. In a water heater, primary and secondary heating coils, means to effect heat transfer with said coils, and means in series 25 with and between the primary and secondary coils and operable by a variation of the temperature of a primary coil for varying the heating effect of said heat transfer 30 means.

2. In a water heater, primary and secondary water coils arranged in series, means to effect heat transfer with one of said coils, and means in conjunction with and controlled by the temperature of the other of 35 said coils for varying the heat transfer rate.

3. In a water heater, primary and secondary coils, a common source of heat therefor, and means in series between a primary 40 coil and a secondary coil and controlled by the temperature of a primary coil for varying the heating rate from said source.

4. In a water heater, a plurality of heater coils arranged in upper and lower tiers, 45 means constructed and arranged to heat said coils simultaneously, and means connected between said coils responsive to variations in water temperature in said lower coil tier to regulate said heater means.

5. In a water heater, a plurality of heating coils arranged in groups, heating means common to each of said groups, fuel supply means for said heater, and thermal-responsive means connected in series with and between 55 said groups responsive to temperature variations to regulate said fuel supply means.

6. In a water heater, a plurality of heating coils arranged in groups, said groups being 60 connected in series and above one another, the coils of each group being connected in parallel, heating means common to all of said groups, means for controlling said heating means, and means thermally-responsive 65 to water temperature variations in a portion

of only one of said groups for regulating said control means.

7. In a water heater, the combination of a plurality of heating coils, a thermostat connected in series with and between said coils 70 only, and means actuated by said thermostat for controlling the temperature of the water delivered from said coils.

8. In a water heater, a plurality of heating coils connected in series only, means for 75 heating said coils, a thermostat through which water flows from one coil to the other, and fuel supply means controlled by said thermostat.

9. In a water supply system, a one way 80 conduit, means for simultaneously heating spaced portions of said conduit, and means forming part of said conduit between said spaced portions for controlling said heating means in accordance with variations of the 85 temperature of the water passing therethrough.

10. In a water heater, a fuel burner, a primary water heating coil adjacent said burner and adapted to be primarily heated thereby, 90 a secondary water heating coil in the path of heated gases from said burner and adapted to be secondarily heated thereby, said primary and secondary coils being connected 95 in series whereby water flowing from said primary coil will pass into said secondary coil and thence to an outlet, and means for controlling the heat supplied by said burner inversely as the temperature of the water 100 passing from the primary coil.

11. In a water heater, a fuel burner, a cold water inlet, a primary water heating coil connected to said inlet adjacent said burner and adapted to be heated by said burner, a secondary water heating coil adapted to be heated by heated gases rising from said burner and past the primary coil, said primary coil being connected in series with the top of the secondary coil only, and a water outlet from the bottom of the secondary coil, 105 whereby all water drawn for use will have passed through said coils in the order named.

12. In a water heater, a fuel burner, a cold water inlet, a primary water heating coil connected to said inlet and situated adjacent 110 and above said burner to be heated by heated gases rising therefrom, a secondary water heating coil above said primary coil and adapted to be heated by gases passing from said burner past said primary coil, a connection from the top of said primary coil to the top of said secondary coil, an outlet from the bottom of the secondary coil, and means intermediate said coils and operatively connected to one of said coils for automatically regulating said burner in accordance with the temperature of the primary coil.

13. In a non-return fluid heating system having an inlet and an outlet, a pair of substantially restricted water passages connect- 115

ed in series with each other and with said inlet and outlet and in fluid tight relation, means for heating said passages by radiation, and means interposed between and in series with said passages for varying the heat supplied from said heating means.

14. In a water heater, a source of heat supply, a cold water inlet, a primary water heating coil connected to said inlet adjacent said source of heat supply and adapted to be heated thereby, a secondary water heating coil adapted to be heated by gases rising

from said source of heat supply past the primary coil, said primary coil being connected in series with the top of the secondary coil only, a water outlet from the bottom of the secondary coil whereby all water drawn for use will have passed through said coils in the order named, and means thermally responsive to water temperature variations in one of said coils for regulating the heat supplied by said source. 15 20

HARRY J. LYONS.
